UNITED STATES PATENT OFFICE.

DANIEL E. DOPP, OF SANTA ROSA, CALIFORNIA.

PIANO-ACTION.

SPECIFICATION forming part of Letters Patent No. 364,399, dated June 7, 1887.

Application filed March 14, 1887. Serial No. 230,903. (No model.)

To all whom it may concern:

Be it known that I, DANIEL E. DOPP, of Santa Rosa, county of Sonoma, and State of California, have invented an Improvement in 5 Piano-Actions; and I hereby declare the following to be a full, clear, and exact description thereof.

My invention relates to piano actions, and especially to those which are adapted for 10 upright pianos; and my invention consists in the novel spring-connections of the hammer-butt and the back-check, by which I avoid the employment of ordinary pivots packed or bushed with cloth, which become 15 subject to dampness, and also by which I am enabled to effect a satisfactory delicacy and rapidity of action; in the adjustability of these spring-connections for the purpose of exactly 20 adjusting the hammer and the back-check; in the peculiar arrangement and relation of the back-check to the hammer-butt and the operating-jack, whereby said back-check is enabled to take the place of said jack after the latter has thrown off from the butt, by which 25 means I am enabled to produce a rapid repeat of the hammer; in the damper, spring, and connection by which said damper is operated, and in the screw-guides for adjusting the jack-extension and other details, all of which I shall 30 hereinafter fully describe.

Referring to the accompanying drawings, Figure 1 is a side elevation of my piano-action. Fig. 2 is a cross-section of the jack-extension 35 *c* on the line of the guide-screws *d*. Fig. 3 is a plan showing the attachment of the adjustable bracket *F* in its seat. Fig. 4 is a vertical section of same.

A is the key-frame, having the balance-rail *a*, over which the key *B* is balanced in the usual manner. The inner end of the key is 40 slotted horizontally near its lower portion, forming a kind of tongue, *b*, upon which the disk-protected end of a screw, *b'*, which passes down through the key, is adapted to bear. It will now be seen that by turning 45 down said screw, so that its lower end forces itself against the tongue *b* of the key, said tongue is pressed down to its limit, and thereupon the body of the key at its inner end is 50 raised by the screw, which has the effect of depressing its outer end, and a reverse move-

ment of the screw produces a reverse movement of the outer end of the key. By these means I am enabled to level the bank of keys of the piano without any difficulty and with 55 much more facility than the usual method of removing the key entirely and placing a washer or washers under it upon the balance-rail. The inner end of the key is also slotted horizontally near its top, forming an upper tongue, *b''*, to the end of which, by means of a single screw, *b'''*, is fixed a bearing, *b''''*, for the jack-extension *c*. The lower end of this screw *b''''* is protected by a bearing-disk which presses upon the main body of the key. It will now be seen 60 that by turning down said screw the tongue *b''* is thereby elevated, which raises the extension *c* and its jack, and a reverse movement of the screw depresses said extension and jack. The object of this vertical adjustment of the 70 jack is of course to bring its operating end into proper relation with the hammer-butt.

C is the jack, which is pivoted at *c'* to the jack-extension *c*, and is provided with a spring, *c''*, as usual, the jack being also limited in its 75 upward movement by the usual stop, *c''''*.

D is the main rail or support for the action, and in the lower portion of this support are inserted two common wood-screws, *d*, having 80 smooth inclined or beveled heads, which project on each side of the upper portion of the jack-extension *c*, which is properly beveled to the same inclination as the heads of the screws. These screws serve as guides for the jack-extension in its vertical movement, and also as 85 means for adjusting said extension sidewise, for by screwing them in or setting them out their beveled heads act upon the beveled sides of the jack-extension with the adjusting effect desired. 90

E is the hammer, having the butt *e*. Instead of pivoting the butt directly to the bar *D* and packing said pivot, I employ the following spring-connection, which serves all the purposes of a pivot and avoids the usual disadvantages of a pivot-connection, the principal one of which is the effect of dampness upon the bushing of the pivot, causing the parts to move hard. 95

In the main rail *D*, is secured, in a manner I shall presently describe, a bracket, *F*, made by bending a single piece of metal, as shown in 100

Fig. 3. In the outer end of the bracket is secured, by means of a split pin, *f*, straddling its inner coil, a coil-spring, *G*, the free end of which is extended and is secured properly to the hammer-butt. It will now be seen that this spring serves as a pivot for the hammer-butt, though the spring itself does not turn on any center, but simply permits the movement of the hammer-butt by reason of the flexibility or springiness of its own coils, and the coils of said spring may be packed with cloth without any disadvantage. The split pin *f* prevents any turning of the spring on a center which is not necessary. This spring-connection of the hammer produces a delicacy and rapidity of movement in said hammer which cannot be acquired by means of a pivot and avoids all objection on the score of dampness.

The bracket *F* is secured in the rail *D* in the following manner: Its inner end or head, *f'*, is inserted in a socket in the rail, while its neck *f''* projects outwardly through a slot therein, which slot binds pretty closely on the neck. A screw, *f'''*, passes down from the top 25 of the rail through the head of the bracket loosely and binds a cap-piece, *f⁴*, thereon. The socket in which the head fits is large enough to permit a side movement of said head, and, therefore, by loosening up the screw *f'''* 30 the whole bracket may be turned sidewise to a proper position, and may be held in the position to which it is adjusted by tightening the screw against the cap-piece *f⁴* on the head of the bracket. In this way the hammer may be 35 properly adjusted. The upper end of the jack bears against the hammer-butt, as usual, and operates said hammer by its vertical movement.

I is the back-check, consisting of a curved 40 piece, to the outer end of which is fitted a head, *i*, adapted to move on its seat and to be set in the position required by means of a set-screw, *i'*. In this way the head of the back-check is rendered adjustable and may be fixed 45 in the proper position. The back-check, instead of being pivoted to the rail or bar *D*, is secured thereto by a spring-connection similar to that which secures the hammer-butt to the rail, and consisting of a coil-spring, *J*, secured 50 to the inner end of the check and mounted in a bracket, *K*, by means of a split pin, *k*, said bracket being fitted to the rail *D* and adapted to be adjusted in its seat by means of the screw *k'* and the cap-piece *k''*, similar to that which 55 I have heretofore described with relation to the bracket *F*. The jack *C* is slotted over the back-check, and the jack-extension *c* is slotted upon said back-check near its spring-connection, whereby it operates the check. This operation of the check by means of the extension *c* of the jack in the manner here shown effects the following purpose in connection with the position and shape of said jack:

It will be seen that when the jack is elevated 60 against the hammer-butt and the hammer thrown forward to deliver its stroke on the wire *W*, the back-check accompanies it, and,

after the hammer has delivered its blow, catches its butt on the recoil, and the jack itself being now thrown off from the butt, the 70 check is held against the butt by means of the jack-extension *c*, and may be made to operate the hammer itself with the jack thrown off entirely, whereby, after the hammer is close to the wire, the jack-extension may cause it to rapidly repeat without the assistance of the jack, thereby taking the place of the jack to accomplish this.

L is the damper, which is operated in the following novel manner: It is supported upon the 80 upper end of a bent spring-stem, *l*, which passes downwardly behind the main rail *D*, and is secured thereto underneath. A strap, *l'*, is secured to this stem and passes through an opening in the main rail *D*, and is secured to the 85 back-check at a point near its inner end, as shown. Therefore, as the check moves up the strap is drawn upon, and the damper is thereby thrown back from the wire, but is allowed to move forward again to its place against the 90 wire upon the return movement of the back-check.

M is the usual soft-pedal bar, and *N* is the usual swell-pedal bar.

Having thus described my invention, what 95 I claim as new, and desire to secure by Letters Patent, is—

1. In a piano-action, a connection for the swinging or hinged parts thereof, such as the hammer-butt, back-check, &c., consisting of a 100 spring attached to said parts and to the supporting-piece, substantially as described.

2. In a piano action, the means for connecting the hammer-butt with the supporting piece or rail, consisting of a coil-spring secured by 105 its free end to the hammer-butt and mounted on the rail or support, substantially as described.

3. In a piano-action, the hammer and its butt and a rail or support therefor, in combination with a bracket secured to said rail or support and a coil-spring fixed in the end of the bracket and having its free end fixed to the hammer-butt, substantially as described. 110

4. In a piano-action, the hammer and its butt and a supporting rail or piece therefor, 115 in combination with a bracket secured to the rail, a coil-spring in the outer end of the bracket and secured by its free end to the hammer-butt, and a split pin passing through 120 the ends of the bracket and straddling the inner end of the coil-spring whereby it is held, substantially as described.

5. In a piano-action, the hammer and its butt and the rail or support therefor, in combination with the bracket *F*, seated in a socket in the rail and held to place by a cap and screw, whereby it may be adjusted from side to side, and the coil-spring secured in the outer end of the bracket and having its free end attached to the hammer-butt, substantially as described. 125

6. In a piano-action, the back-check having its inner end secured to the rail or support by a coil-spring, substantially as described, 130

7. In a piano-action, the back-check and a rail or support therefor, in combination with a bracket secured to the rail or support and a coil-spring secured in the outer end of the bracket and having its other end attached to the back-check, substantially as described.
8. In a piano-action, the back-check and the rail or support therefor, in combination with the bracket K, secured in a socket in the rail or support, the screw and cap by which it is held and which permit its adjustment, and the coil-spring secured in its outer end and having its free end attached to the back-check, substantially as described.
- 15 9. In a piano-action, the hammer and its butt and the back-check operating against the butt of the hammer, in combination with the vertically-moving jack operating against the hammer-butt, and the jack-extension e, operating on the back-check, whereby said check
- is made to take the place of the jack after said jack is thrown off, thereby operating the hammer for a repeat, substantially as described.
10. In a piano-action, the main rail D and the vertically-movable jack-extension e, in combination with the bevel headed screws in the main rail bearing against the sides of the jack-extension, whereby the latter is guided and may be adjusted, substantially as described.
11. In a piano-action, the combination of the movable back-check, the damper having the spring-shank, and the strap connecting said spring-shank with the back-check, substantially as described.

In witness whereof I have hereunto set my hand.
